Otto Herzmann

UNITED STATES PATENT OFFICE

1,922,243

COVER FOR THE OPENINGS OF COOKING
STOVE HOT PLATES

Otto Herzmann, Essen, Germany

Application July 16, 1930, Serial No. 470,009, and
in Germany July 23, 1929. Renewed January
13, 1933

4 Claims. (Cl. 126—211)

The invention relates to covers for the openings of cooking stove hot-plates and has for its object to increase the efficiency of covers for this class.

5 An embodiment of the subject-matter of the invention is illustrated by way of example in the accompanying drawing in which.

Figure 1 is a cross section through the cover.
Figure 2 is a top view of the cover.

10 Figure 3 is a sectional view of a suction nozzle on an enlarged scale.

Figure 4 is a sectional view of a damper of the cover likewise on an enlarged scale.

15 A hot plate *a* has inserted in it a cover *b* which possesses on its underside a flue open toward the source of heat and extending in a spiral line. This flue is formed by a vertical spiral rib *c* projecting from the cover *b*. On the outer end of the flue thus formed is provided an adjustable damper *h*, see also Figure 4. The rib *c* includes a plurality of nozzles *d*, see also Figure 3, having each a lower aperture *g* and an upper outlet port *f* extending about tangentially to the spiral line of the flue.

20 25 The described cover *b* is inserted in the hot plate *a* in such a manner that the outer end of the flue is turned toward the smoke pipe of the furnace, with the damper *h* in open position. A portion of the smoke gases then streams through the flue on the underside of cover *b* whereby, as tests have shown, an increased transmission to heat the plate *b* is obtained. As the inventor has observed, a sucking action takes place in the suction nozzles *d* whereby the flow of the heating gases in the flue is increased. This flow can be regulated by suitably adjusting the damper *h*

or by turning the whole cover *b* relatively to plate *a*.

What is claimed is,—

1. In a furnace of the class described a stove hot-plate, a heating-opening therein, a cover fitting into the said heating-opening, and hollow-spaces formed on its interior surface adapted for receiving the heating gases, said hollow-spaces forming a flue extending in a spiral line and being open at its outer end. 30

2. In a furnace of the class described a stove hot-plate, a heating-opening therein, a cover fitting into the said heating-opening, hollow-spaces formed on its interior surface adapted for receiving the heating gases, and means arranged on the cover for sucking the heating gases into the hollow-spaces. 70

3. In a furnace of the class described a stove hot-plate, a heating-opening therein, a cover fitting into the said heating-opening, hollow-spaces formed on its interior surface adapted for receiving the heating gases, and suction nozzles arranged on the cover for sucking the heating gases into the hollow-spaces, each consisting of an inlet opening turned towards the arriving heating gases and an outlet opening arranged about tangentially to the spiral line of the flue. 75 80

4. In a furnace of the class described a stove hot-plate, a heating-opening therein, a cover fitting into the said heating-opening, hollow-spaces formed on its interior surface adapted for receiving the heating gases, said hollow-spaces forming a flue extending in a spiral line and an adjustable damper arranged at the outlet opening of the flue. 85 90

OTTO HERZMANN.
